DESIGN.

E. L. CALEY.
FIRE PLACE GRATE.

No. 19,253.

Patented Aug. 6, 1889.

UNITED STATES PATENT OFFICE.

EDWARD L. CALEY, OF PHILADELPHIA, PENNSYLVANIA, ASSIGNOR TO GILBERT COMBS, JOHN BAWDEN, AND JOHN H. BAWDEN, OF FREEHOLD, NEW JERSEY.

DESIGN FOR A FIRE-PLACE GRATE.

SPECIFICATION forming part of Design No. 19,253, dated August 6, 1889.

Application filed January 9, 1889. Serial No. 295,884. Term of patent 7 years.

To all whom it may concern:

Be it known that I, EDWARD L. CALEY, a citizen of the United States, and a resident of Philadelphia, Pennsylvania, have invented 5 a new and original Design for a Portable Fire-Place Grate, of which the following is a specification.

My design is fully shown in the accompanying photographic illustration, the general appearance of the design being that of lattice-work combined with quadrangular blocks, the main panels of the back and sides being composed of a series of such quadrangular blocks.

The decoration of the back and side plates 15 consists of a series of quadrangular blocks formed by beveled grooves, so that each block is beveled on its four sides, and each block has a central circular projection surrounded by a ring, and radiating from this ring are a 20 series of raised lines. Above the panels of the back and sides are open-work panels of lattice-work, forming quadrangular openings between the bars of the lattice, and at the junction of the bars are circular depressions 25 with studs therein. The outline of the front plate is the same as that of the panels last described, and consists of lattice-work form-

ing quadrangular openings. At the junctions of the longitudinal and vertical bars of the lattice are circular depressions with studs. 30

I claim—

1. In a design for a fire-place grate, the design for the back plate, consisting of the series of quadrangular blocks with lattice-work above, substantially as described, and as illustrated in and by the accompanying photographic illustration. 35

2. In a design for a fire-place grate, the design for the front plate, consisting of a series of vertical bars and a series of longitudinal bars crossing each other and forming lattice-work, with a circular depression and a stud at the junction of the vertical and longitudinal bars, substantially as shown and described. 40

3. The design for a fire-place grate, substantially as shown and described. 45

In testimony whereof I have signed my name to this specification in the presence of two subscribing witnesses.

EDWARD L. CALEY.

Witnesses:

WILLIAM D. CONNER,
HARRY SMITH.
